UNITED STATES PATENT OFFICE.

JAMES E. STEPHENSON, OF ROCHESTER, NEW YORK, ASSIGNOR TO GENERAL RAILWAY SIGNAL COMPANY, OF ROCHESTER, NEW YORK.

SNUBBING CIRCUITS FOR SEMAPHORE SIGNALS.

Application filed May 25, 1925. Serial No. 32,751.

This invention relates to railway signaling and more particularly concerns a circuit arrangement for use in connection with the usual motor operated semaphore signals of 5 railways.

In modern railway practice, particularly on railroads where congested traffic conditions exist, the well known automatic three-position type of block signaling is often 10 used. In a signaling system of this type, semaphore wayside signals are frequently employed of the type in which the semaphore blade and spectacle are biased to their danger position by gravity or other suitable 15 means, are raised to their caution and clear positions by a small electric motor and are retained in the caution and clear positions by suitable electrically operated latching means. When the latching means is released and the 20 semaphore blade with its associated mechanism is suddenly biased from a clear or caution position to a caution or danger position, the momentum acquired by the blade and its comparatively heavy spectacle in their 25 downward or biased movement causes undue and injurious strains on the comparatively delicate signal and operating mechanism when this mechanism is brought to a sudden stop.

With the above and other considerations in mind it is proposed in accordance with the present invention to provide a three-position semaphore operating mechanism which incorporates means for preventing injurious slaming of parts when the 35 movable signal mechanism is brought to a stop, and more specifically, it is proposed to provide means in connection with the operating circuits of a signal of this type for dynamically snubbing the biased motion of the semaphore blade and spectacle by causing a 40 circuit through the operating motor to be closed through a resistance during the biased motion of the blade.

Further objects, advantages and characteristic features of the present invention will become apparent as the description thereof progresses.

In describing the invention in detail, reference will be made to the accompanying drawing, in which a single figure has been shown, representing in a diagrammatic and conventional manner, a section of trackway 50 provided with automatic block signals, together with the devices and circuits for op-

erating the same in accordance with the present invention.

Referring to the drawing, the track rails 1 have been shown divided into the usual blocks by the insulated joints 2, the block J 60 and the ends of the two adjacent blocks I and K having been shown. As the signal mechanism and control apparatus associated with each block is identical, a detailed description of that associated with one block 65 only will be given, the corresponding elements associated with the adjacent blocks being referred to by like reference characters having distinctive exponents.

A track relay 3 is connected across the 70 track rails at the entrance end of each block, this relay being of the well known polar neutral type, that is, this relay has a polar armature which is biased to one or the other of two positions by the polarity of the current impressed on the relay windings, and has another armature which is moved to either one of two positions by the energization and de-energization of the relay windings, regardless of polarity. The energy for 75 operating the track relay 3 is supplied by a track battery 4, located at the exit end of the block, and connected across the track rails through the pole changing neutral contacts 5¹ and 6¹ of the track relay 3¹ of the 80 advance block as clearly shown, so that the polarity of the track circuit current in a given block will be reversed when the track relay in the next block in advance is de-energized.

As the general structure and organization of the mechanical details of the signal operating mechanism form no part of the present invention, and as this structure is well known by those skilled in the art, the 85 semaphores have been illustrated in a conventional manner only at 7, the operating motor, the operating means for the latching device and the control circuits and devices 90 therefore being shown diagrammatically.

The operating motor 8 is in the present instance of the direct current type, though any other suitable motor might be used, and it is assumed to be connected with the semaphore arm through a suitable shaft and train of reduction gears. The signal operating mechanism includes two holding coils H and I, of high and low resistances respectively, it being assumed that the energization 105 of the holding coil H will serve to retain 110

5 a suitable latching device in a position to hold the semaphore blade in its clear or caution position, but will not move the latching device to this position; while the energization of the holding coil L will move the latching device from its free or unengaged position to its engaged position.

10 Suitable contact fingers 9, 10, and 11, operated in accordance with the position of the semaphore blade, are provided to control the operation of the signal mechanism. The finger 9 is arranged to engage a stationary contact segment 12 when the semaphore blade is in the danger position and until just before the blade has reached the caution position, and to engage the stationary contact 13 just before the semaphore blade reaches its caution position and until just before the blade has reached its clear position. The contact finger 10 is arranged to engage the stationary contacts 14 and 15 when the semaphore blade is in its caution and clear positions respectively. The contact finger 11 is arranged to engage the stationary contact segment 16 just as the blade completes its motion from the danger to the caution position, and to engage the stationary contact segment 17 just as the blade completes its motion from the caution to the clear position. The relative position of the stationary contact 12 to the stationary contact 16, the stationary contact 13 to the stationary contact 17 are so arranged that the contact finger 11 engages the stationary contact 16 just before the contact finger 9 disengages the stationary contact 12, and the finger 11 engages the stationary contact 17 just before the finger 9 disengages the stationary contact 13, also the contact finger 10, engages its contacts 14 and 15 by the time finger 9 leaves its contacts 12 and 13 respectively.

Operation.

45 With the block J and the block K in advance thereof unoccupied, track circuit current of normal polarity will be impressed upon the track rails of the block J and upon the winding of the track relay 3 through a circuit which may be traced as follows:—
50 from the positive terminal of the track battery 4, front contact and neutral contact finger 6¹ of the track relay 3¹, wire 18, track resistance 19, wire 20, one track rail 1 of the block J, wire 21, winding of the track relay 3, wire 22, the other track rail of the block J, wire 23, contact finger 5¹ and front contact of the track relay 3¹, and wires 24 and 25 to the negative terminal of the battery 4.
55 With the track relay 3 energized by track current of normal polarity, its polar contact finger 26 will be held in the position shown, the semaphore blade will be in its normal or clear position, and an energizing circuit for the high resistance holding coil H will be

60 maintained which circuit may be traced as follows:—from the positive terminal of the signal operating battery 27, wire 28, front contact and neutral contact finger 29 of the track relay 3, wires 30 and 31, stationary contact 32 and polar contact finger 26 of the track relay 3, wires 33 and 34, stationary contact 15 and contact finger 10, wire 35, winding of the high resistance holding coil H, wires 36 and 37, finger 11 and stationary contact 17, wires 38, 39 and 40, winding of the signal operating motor 8, and wires 41, 42 and 43 to the negative terminal of the battery 27. With the holding coil H energized, the signal mechanism will be maintained in its clear position by a suitable latching device controlled by the holding coils.

65 Considering now a change from clear to danger conditions, if a train enters the block J from the block I, the track circuit current is shunted from the track relay 3 by the wheels and axles of the train and this relay is consequently de-energized and retracts its neutral contact fingers 29, 5 and 6. The 70 polar contact finger 26 remains in the position shown until a current of reverse polarity flows in the track relay. When the neutral contact finger 29 disengages its front contact, the energizing circuit to the high 75 resistance holding coil H, traced above, is broken, the latching device is released, and the semaphore blade begins to drop, being biased by gravity or other suitable means. Shortly after the semaphore blade leaves its 80 clear position, the contact finger 9 engages its stationary contact segment 13, and a snubbing circuit through the operating motor 8 is completed, which circuit may be 85 traced as follows:—from the motor 8, wires 90 40 and 44, contact finger 9 and stationary contact 13, wires 45 and 33, polar contact finger 26 and stationary contact 32 of the track relay 3, wires 31 and 30, contact finger 29 and back contact of the relay 3, wires 46 95 and 47, snubbing resistance 48, and wires 49, 42 and 41 to the operating motor 8. The snubbing resistance 48, included in the circuit just traced, limits the flow of current generated by the motor 8 which operates to 100 generate a current in the well known manner during the biased movement of the semaphore blade, and the mechanism is thereby snubbed or dynamically braked by the motor. As the semaphore blade passes the caution position, the contact finger 9 engages its 105 stationary contact 12 and a second snubbing circuit for the motor is completed, which circuit may be traced as follows:—from the operating motor 8, wires 40 and 44, contact finger 9 and stationary contact 12, wires 50 110 and 30, contact finger 29 and back contact of the track relay 3, wires 46 and 47, snubbing resistance 48, and wires 49, 42 and 41 to the operating motor 8. It will be noted 115 120 125 130

that as the stationary contact 13 overlaps the end of the stationary contact 12 at the caution position, one or the other of the snubbing circuits just traced is always maintained closed, and the descent of the semaphore blade is therefore continuously restricted, the mechanism being thereby protected against injurious shocks or jars which would occur if the semaphore blade was allowed to drop freely and was suddenly brought to a stop in its danger position.

As the train passes out of the block J and into the block K, the shunt is removed from the track rails of the block J and the neutral contact fingers 29, 5 and 6 of the track relay 3 are picked up, picking up of track relay finger 29 breaking the snubbing circuit through motor 8. The train being located in the block K, the track relay 3¹ of that block is de-energized, and its neutral contact fingers 5¹ and 6¹ are retracted, reversing the polarity of the track circuit current in the block J through a circuit which is obvious from the drawings. The track relay 3 of the block J being supplied with a current of reverse polarity, attracts its polar contact finger 26 to the reversed position, that is, the position shown by the dotted line, and an energizing circuit for the signal operating motor 8 is completed, which circuit may be traced as follows:—from the positive terminal of the battery 27, wire 28, front contact and neutral contact finger 29, wires 30 and 50, stationary contact 12 and contact finger 9, wires 44 and 40, winding of the signal operating motor 8, and wires 41, 42 and 43 to the negative terminal of the battery 27. The motor 8 being thus energized operates the signal mechanism and raises the semaphore blade to its caution position. Just before the signal has reached the caution position, and before the contact finger 9 has disengaged the stationary contact 12, the finger 11 engages the stationary contact 16 and a circuit for energizing the low resistance holding coil L is completed, which circuit may be traced as follows:—from the positive terminal of the battery 27, wire 28, front contact and neutral contact finger 29 of the track relay 3, wires 30 and 50, stationary contact 12 and contact finger 9, wires 44, 39 and 51, stationary contact 16 and contact finger 11, wires 37 and 52, winding of the low resistance holding coil L and wires 53, 42 and 43 to the negative terminal of the battery 27. The low resistance holding coil L now picks up the latching device to hold the signal mechanism in its caution position, and as the mechanism reaches this position an energizing circuit for the high resistance holding coil H is completed, which circuit may be traced as follows:—from the positive terminal of the battery 27, wire 28, front contact and neutral contact finger 29 of the

track relay 3, wires 30, 50 and 54, stationary contact 14 and contact finger 10, wire 35, winding of the high resistance holding coil H, wires 36 and 37, contact finger 11 and stationary contact 16, wires 51, 39 and 40, winding of the operating motor 8 and wires 41, 42 and 43 to the negative terminal of the battery 27. The circuit through the low resistance holding coil L, traced above, is broken just before the signal reaches the caution position by the disengagement of the contact finger 9 and the stationary contact 12, so that only the small amount of current necessary to energize the high resistance holding coil H is flowing when the signal mechanism is not in actual operation, this arrangement effecting a desirable saving in the amount of energy consumed.

Just before the signal 7 reaches its caution position finger 9 breaks contact with 12, and thus interrupts the motor circuit traced above.

As the train passes out of the block K, the track relay 3¹ of this block is again energized, attracting its neutral contact finger 5¹ and 6¹, and causing track circuit current of normal polarity to flow in the block J. The polar contact finger 26 of the track relay 3 is now moved to its normal position as shown, and the signal mechanism is operated to its clear position in a manner similar to that described above in connection with the operation from the danger to the caution position. The operating motor 8 is energized through a circuit which may be traced as follows:—from the positive terminal of the battery 27, wire 28, front contact and neutral contact finger 29 of the track relay 3, wires 30 and 31, stationary contact 32 and polar contact 26 of the track relay 3, wires 33 and 45, stationary contact 13 and contact finger 9, wires 44 and 40, windings of the operating motor 8 and wires 41, 42 and 43 to the negative terminal of the battery 27. The motor 8 drives the mechanism to its clear position, and just before the clear position is reached, an energizing circuit for the low resistance holding coil L is completed, which circuit is traceable as follows:—from the positive terminal of the battery 27, wire 28, front contact and neutral contact finger 29 of the track relay 3, wires 30 and 31, stationary contact 32 and polar contact finger 26 of the relay 3, wires 33 and 45, stationary contact 13 and contact finger 9, wires 44, 39 and 38, stationary contact 17 and contact finger 11, wires 37 and 52, winding of the low resistance holding coil L and wires 53, 42 and 43 to the negative terminal of the battery 27. The low resistance holding coil L is de-energized as the signal reaches its clear position and the contact finger 9 disengages the stationary contact 13, and at this time an energizing circuit for the

high resistance holding coil H is completed, which circuit has been traced above.

It should be understood that the latching device used restricts the motion of the signal mechanism in one direction only, that is, its motion from clear to caution or caution to danger position, and when the motor is energized to lift the semaphore plate from its danger to its caution position or from its caution to its clear position, the energization of the high resistance holding coil H will not prevent the upward motion of the blade. The circuit through the holding coil is broken as soon as the semaphore blade has started to move by the disengagement of the stationary contacts 14 or 15 by the contact finger 10, so that the latching device does not drag, and energy for the coil H is not wasted.

20 It sometimes occurs that traffic conditions in a given block change from clear to danger by reason of the breaking of a track rail, the opening of a track switch or the backing of a train into the block. Assuming that traffic 25 conditions have in this manner changed from clear to danger in a given block, say the block K, the track relay 3¹ at the entrance end of this block is de-energized, detracting its contact fingers 5¹ and 6¹, and so reversing 30 the polarity of the track circuit current flowing through the track relay 3 of the block J. The polar contact finger 26 of the track relay 3 now assumes its reverse position as represented by the dotted line, thereby breaking 35 the energizing circuit in the holding coil H, which circuit has been traced above, and so releasing the signal blade operating mechanism. As the signal blade is moved by gravity toward its caution position, a snubbing 40 circuit through the motor 8 is completed, which circuit may be traced as follows:—from the snubbing resistance 48, wire 47, stationary contact 55 and contact finger 26 of the track relay 3, wires 33 and 45, sta- 45 tionary contact 13 and movable contact finger 9, wires 44 and 40, winding of the motor 8, and wires 41, 42 and 49 to the snubbing resistance 48. The signal blade continues its downward motion, being yieldingly 50 resisted by the snubbing of the motor 8, until it has passed beyond the caution position, when the snubbing circuit, traced above, is broken by the disengagement of the contact finger 9 and the stationary contact 13. 55 When the signal blade moves a few degrees beyond the caution position, the contact finger 9 engages its stationary contact 12, and an energizing circuit for the motor 8 is completed, which circuit may be traced as 60 follows:—from the positive terminal of the battery 27, wire 28, front contact and contact finger 29 of the track relay 3, wires 30 and 50, stationary contact 12 and contact finger 9, wires 44 and 40, motor 8, and wires 41, 42 and 43 to the negative terminal of the

battery 27. The motor 8 now operates to move the signal blade to its caution position, and as the caution position is reached, an energizing circuit for the low resistance holding coil L is completed through the stationary contact 16 of the movable contact, this circuit having been traced above. The latching device is operated by the energization of the holding coil L to maintain the signal blade in its caution position, and, as the signal blade comes to a stop in its caution position, the energizing circuit for the low resistance holding coil L is broken by the disengagement of the stationary contact 12 and the movable contact finger 9, and an energizing circuit for the high resistance holding coil H is completed through the contact finger 10 and the stationary contact 14, this energizing circuit having been traced above. It is thus evident that when the signal blade moves from its clear to its caution position, a snubbing circuit through the motor 8 is completed and the motion of the signal blade is thereby yieldingly resisted, thus preventing injurious slamming of the signal operating parts.

It will be seen that by the arrangement of circuits and contacts of the present invention, a semaphore operating arrangement has been devised in which the biased motion of the signal mechanism is effectively snubbed or retarded by the dynamic braking effect obtained by closing the operating motor circuit through a resistance during such biased motion of the mechanism. This snubbing action imparts a smooth and slow motion to the semaphore blade and its associated mechanism, and substantially reduces jars, shocks and slams, thus increasing the life of the various parts of the mechanism.

The present invention has been shown and described in connection with rather specific circuits and devices, and it should of course be understood that the various means shown and described are capable of certain modification and rearrangement without departing from the spirit of the present invention as defined by the appended claims.

What it is desired to secure by Letters Patent is:—

1. In a three-position railway signal, means for operating a biased semaphore blade including a motor for moving said blade from its biased position, a track relay, an energizing circuit for said motor, and a snubbing circuit for short circuiting the motor through a resistance in series with a contact of the track relay while said semaphore blade moves to its biased position.

2. In a semaphore railway signal of the three position type, a semaphore blade biased to its danger position, a motor for moving said blade to its caution or clear positions and means for controlling the operation of said motor and said blade comprising

contacts operated in accordance with the position of said blade and contacts operated by a polar neutral relay for energizing said motor to move said blade under certain conditions and for connecting said motor in series with a resistance for opposing the biased motion of said blade under other conditions.

3. In a semaphore railway signal of the 10 three-position type, a semaphore blade biased to its danger position, a motor for moving said blade to its caution or clear positions and means for controlling the operation of said motor and said blade comprising contacts operated in accordance with the position of said blade and contacts operated by a polar neutral relay and circuits controlled by said contacts for energizing said motor to move said blade to the caution position 20 when said relay is energized by current of a certain polarity, for energizing said motor to move said blade to the clear position when said relay is energized by current of an opposite polarity and for closing a series snubbing circuit through said motor to yieldingly resist the biased motion of said blade when said relay is de-energized.

4. In a railway semaphore signal having clear, caution and danger indicating posi-

tions, a semaphore blade biased to its danger 30 indicating position, an electric motor for moving said blade to its caution and clear positions, a pick-up coil and a holding coil acting when energized to respectively operate and maintain operated a means for retaining said blade in its caution or clear positions, a resistance unit, and a polar neutral relay for controlling the energization of said motor and said coils and for closing a 35 series circuit through said motor and said 40 resistance unit when said holding coil is de-energized to permit said blade to be biased from its clear or caution positions to its danger position.

5. In a railway signal of the type having a semaphore blade movable to three indicating positions and biased to one of its extreme positions, a motor for lifting said blade from its biased position to either of its other two indicating positions, means for 45 maintaining said blade in either of said other two positions, a track relay, and means to short circuit the motor through a contact of the track relay for opposing the biased motion of said blade. 55

In testimony whereof I hereby affix my signature.

JAMES E. STEPHENSON.
